UNITED STATES PATENT OFFICE.

GIDEON SIBLEY, OF PHILADELPHIA, PENNSYLVANIA.

ARTIFICIAL TOOTH.

No. 910,870.

Specification of Letters Patent.

Patented Jan. 26, 1909.

Application filed May 12, 1908. Serial No. 432,344.

To all whom it may concern:

Be it known that I, GIDEON SIBLEY, a citizen of the United States, and resident of the city and county of Philadelphia, and 5 State of Pennsylvania, have invented certain new and useful Improvements in Artificial Teeth, of which the following is a specification.

This invention relates to that class of 10 artificial teeth wherein facings, of porcelain or the like, are detachably secured to a metallic backing, such, for example, as illustrated in Letters Patent of the United States, Nos. 651,388 and 792,618, dated 15 June 12, 1900 and June 20, 1905, respectively, of which I am the assignee.

The object of the present invention is to produce, in artificial dentures, a novel and meritorious construction whereby the tooth 20 facing or facings shall be readily and effectively interlocked with the backing, and yet be readily removable therefrom individually for repair, if necessity should require.

Accordingly, my invention stated generally, consists in providing the tooth-facing with a rearwardly-projecting loop, preferably of flat metal, and in providing the backing with a socket or recess, having at its mouth a depending pin, the parts being so 30 constructed and arranged relatively to each other that upon the application of the facing to the backing, the loop shall enter the recess and receive and embrace the pin in a manner to insure the efficient interengagement of the 35 facing and backing, as will be hereinafter described and claimed.

In the drawings—Figure 1 is a front view of a bridge embodying my invention, one of the facings being omitted to expose the metallic 40 backing. Fig. 2 is a perspective view of one of my improved tooth-facings, showing the loop on the rear thereof. Fig. 3 is a similar view of a part of a plate or backing, showing the recess or socket and the retaining pin 45 therein. Fig. 4 is a vertical section through the associated facing and backing, as on the line 4—4 of Fig. 1.

A is a facing of porcelain, or other refractory substance; and B the metallic backing 50 therefor, which latter may constitute part of a crown, plate, bridge, or other basal portion. The facing is provided on its rear with an outwardly projecting rectangular loop, *a*, preferably of flat metal, the legs of which are 55 embedded in the porcelain when molded,

and then baked therein, so as to constitute, in effect, an integral part of the facing. The loop may be otherwise affixed to the facing, if desired.

The metallic backing has formed therein, 60 by stamping or otherwise, a shallow socket or recess *b*, the bottom *b'* of which inclines from its lower forward edge, upwardly and rearwardly, as indicated. The width of this recess is co-extensive with that of the outwardly-projecting loop *a*, or substantially so.

In the roof *b* of the recess is formed a vertical aperture *b*², through which extends longitudinally of the recess and at the mouth thereof, a pin *b*⁴, the reduced and shouldered 70 upper portion of which takes against, and is soldered or otherwise rigidly affixed to, the rear of the backing, as at *b*⁵. The outer face of the pin at the mouth of the recess is flush with the front of the backing, or substantially so, and is of a width to enter snugly into and between the parallel legs of the loop, and be held therein by friction, the lower portion of the pin being preferably beveled or inclined on its inner side, as indicated. This 75 portion of the pin terminates at a point above the lower edge of the recess.

The facing and backing just described are associated by entering the projecting loop into the lower portion of the recess of the 80 backing, and then forcibly pressing the facing upwardly with respect to the backing; a suitable cement first having been applied to the contiguous surfaces of the parts. Thus the flat walls of the loop embrace the depending portion of the pin, and by the wedge-like action of the beveled surface of the latter upon the transverse limb of the loop, the 85 loop is drawn rearwardly into the recess and against the inclined wall thereof, in a manner to force the facing into close contact with the backing and the outer side of the pin, which, together with the lateral support afforded by the frictional engagement of the flat side of the loop with the opposing surface of the 90 pin and the lateral walls of the recess, insure an efficient interlocking of the facing and 95 backing. Preferably, though not essentially, the lower edge of the backing is formed, as at *b*⁶, to engage and protect the incisive 100 end of the tooth facing, when the latter is applied.

By the construction hereinbefore described, I provide a connection between the tooth facing or facings and the backing, 110

which, while simple and effective, permits the ready removal and renewal of any facing without affecting the remainder of the denture.

5 I claim—

1. An artificial tooth comprising a facing of porcelain, or the like, having affixed thereto a rearwardly projecting loop, in combination with a metallic backing having a recess and a retaining pin permanently secured at one end to said backing so as to depend at or adjacent the mouth of the recess, whereby the said loop, by relative movement of the facing and backing, can be seated within the recess and engaged with the pin.
2. An artificial tooth comprising a facing of porcelain, or the like, having affixed thereto a rearwardly projecting loop, in combination with a metallic backing having a recess with an inclined wall, and a depending retaining pin, said pin permanently secured to the backing being adapted to enter the said loop when the latter is applied to the recess.
3. An artificial tooth comprising a facing of porcelain, or the like, having affixed thereto a rearwardly projecting loop of flat metal, in combination with a metallic backing having a recess with an inclined inner wall and of a width co-extensive with that of the loop, and a retaining pin affixed to the backing and depending into the recess at the mouth thereof, said pin being beveled on its inner side and being adapted to enter the said loop when the latter is applied to the recess.

4. An artificial tooth comprising a facing of porcelain, or the like, having affixed thereto a rearwardly-projecting loop, in combination with a metallic backing having a recess with an apertured roof, and a retaining pin having a reduced shouldered portion extending through the aperture of the roof and rigidly affixed to the backing, said pin being adapted to enter the said loop when the latter is applied to the recess.

5. A backing for artificial teeth, comprising a metallic plate having a shallow socket or recess, and a rigid pin permanently secured at one end to said plate so as to depend at or adjacent the mouth of said socket or recess and terminate at a point above the lower edge thereof.

6. A backing for artificial teeth, comprising a metallic plate having a shallow socket or recess with an apertured roof, and a pin having a reduced shouldered portion extending through the aperture of the roof and rigidly affixed to the plate, said pin depending at or adjacent the mouth of said socket or recess and terminating at a point above the lower edge thereof.

Signed at the city and county of Philadelphia, and State of Pennsylvania, this second day of May, 1908.

GIDEON SIBLEY.
